UNITED STATES PATENT OFFICE.

GROVER CLEVELAND HARALSON AND WILLIAM ERNEST TURNER, OF ATLANTA,
GEORGIA.

FILLING OR THREAD HOLDER FOR LOOMS.

1,385,914.

Specification of Letters Patent. Patented July 26, 1921.

Application filed June 30, 1920. Serial No. 393,204.

To all whom it may concern:

Be it known that we, GROVER CLEVELAND HARALSON and WILLIAM ERNEST TURNER, citizens of the United States, residing at 5 Atlanta, in the county of Fulton and State of Georgia, have invented certain new and useful Improvements in Filling or Thread Holders for Looms; and we do hereby declare the following to be a full, clear, and 10 exact description of the invention, such as will enable others skilled in the art to which it appertains to make and use the same.

This invention relates to weaving looms and more particularly to an attachment 15 therefor which will be hereinafter known as a filling clamp, the object of the invention being the provision of novel means for acting upon the filling at the time the latter, if properly laid, engages the usual filling fork 20 so that the operation of the latter is rendered more accurate and effective.

In order that the filling shall tilt the fork, it is common to provide the lay with a rack or grate to support the filling in front of the 25 fork as the lay beats up and sometimes this device has been reinforced by putting more tension on the filling in the shuttle. Both of these devices are objectionable, because lint is liable to choke the grate and impair the 30 proper action of the fork and owing to the closeness of the grate bars to each other, any looseness in the lay or the fork support will cause the tines of the fork to strike the grate and prevent the detecting action of the fork, 35 while the increased tension of the fork on the shuttle causes the filling to pull too hard on the selvage when the shuttle is going across the lay.

It is one of the main objects of our invention to do away with this filling rack and provide suitable means which will effectively engage and retain the lay threads in a tight 40 position after being drawn across the warp threads, thus preventing any slack in the lay threads, which causes loose weave in the cloth.

Another object of the present invention is the provision of a filling clamp for looms, adapted to be operated simultaneously with 45 the movement of the lay, whereby the filling clamp head will automatically contact with the lay thread and clamp the same against the back of the shuttle box after the lay thread has been drawn across the warp

threads and the shuttle is in its position 55 within the box prior to returning across the warp threads, and upon the rearward movement of the lay, the clamp will be automatically removed from contact with the lay thread and permit the shuttle to return 60 to the opposite side of the lay, the clamp being operated through the movement of the lay.

With the above and other objects in view, the invention consists in the combination 65 and arrangement of parts hereinafter more fully set forth, pointed out in the claims and shown in the accompanying drawings, in which—

Figure 1 is an end elevation of a weaving 70 loom illustrating our improved filling clamp attached thereto,

Fig. 1^a is a detailed front elevation showing the relative positions of the clamp rod and the filling brake,

Fig. 2 is a transverse sectional view of the means for supporting the filling clamp and rod onto the loom frame,

Fig. 3 is a sectional view taken on the line 3—3 of Fig. 2,

Fig. 4 is a transverse sectional view taken through the clamping head illustrating the use of a flat spring for tension,

Fig. 5 is a similar view, illustrating the use of coil springs,

Fig. 6 is another cross-section of the clamping head, taken at right angles to Fig. 5, and

Fig. 7 is a detailed sectional view taken on the line 7—7 of Fig. 1.

Referring now more particularly to the 90 drawings, the numeral 1 indicates the frame work of a weaving loom and 2 the lay supporting rod which is mounted for pivotal movement upon the frame as shown at 3. The lay rod supports the lay 4 and in the 95 present illustration, we have illustrated that portion of the shuttle box as indicated at 5.

Secured to one of the horizontal portions of the frame 1 is a U-shaped clamping member 6, one end of which is bolted to the horizontal portion of the frame by means of the bolt 7, said bolt extending through the frame and having mounted upon its outer end, the rod 8 secured in position by means of the nut 9. The lower end of the rod 8 is connected 100 to a portion of the frame 1 by means of the usual coil tension spring 10, the upper end of said brake rod being provided with a

handle member 11. This rod is the customary operating lever for the loom. Mounted for pivotal movement upon the other arm of the U-shaped bracket 6 is a block 12 provided with a suitable opening through which the filling clamp rod 13 extends, said rod being retained in vertical adjusted position within this block 12 by means of the set screw 14.

10 The lower end of the filling clamp rod 13 is connected to the lay supporting rods 2 by means of a clamping member 15 which is formed of a single strip of flat metal having its intermediate portion brought together to form an arm 16, having extensions at its outer end provided with arcuate pockets 17 adapted to embrace the rods 2 and in order to retain the arcuate portion 17 into clamping engagement with the rods 2, the portions at 16 are clamped together by means of a bolt 18 provided with a nut 19 and this bolt 18 also clamps in position the pin 20 which is disposed in the intermediate portion of the strip as illustrated at 21. Connected to the eye 22 of this pin 20 is a coil spring 23, the other end of said coil spring being connected by means of the pin 24 to the lower end of the filling clamp rod 13. It will be noted that by connecting the rod 13 to spring 23 the same will be moved to an oblique position, clamping the thread 28 against the lay frame upon the forward beat of the same. The upper end of the filling rod 13 is provided with a removable brake head 25, having a pocket 26 formed in the face thereof, in which is arranged the clamp member 27, this clamp member 27 which clamps the lay thread 28 against the rear wall of the shuttle box is formed of felt, rubber or any other suitable material and is yieldably mounted within the pocket 26 and provided with a tension spring 29. In the present instance, the tension spring 29 is formed of the flat leaf type.

In Figs. 5 and 6, we have illustrated the brake head as provided with coil tension springs 30 disposed within the pocket 26 and arranged between the clamp member 27 and the inner wall of the pocket 26 to provide suitable tension for the brake member 27 when it contacts with the rear wall of the shuttle box.

What we claim is:

1. A tensioning device, including a loom frame, a clamping member mounted for adjustment thereon, a rod adjustable within the clamping member and means for yieldably connecting the lower end of said rod to the lay of the loom.

2. A tensioning device, including a loom frame, a rod adjustably mounted on said frame, means for adjustably connecting the lower end of said rod to the lay supporting rod of the loom, a yieldable clamping head on the upper end of the rod, and yielding means connecting the rod with the adjustable connecting means.

3. A tensioning device, including a rod, means for adjustably mounting said rod upon a loom frame, means for adjustably and yieldably connecting the lower end of said rod with the lay frame, whereby said rod will be actuated upon the movement of the lay frame, and a yieldable clamping head carried by the upper end of said rod, as and for the purpose set forth.

4. A tensioning device of the class described, including a rod mounted for adjustment on a loom frame, a clamping member adjustably mounted upon the lay rod of the loom, means for yieldably connecting the first rod with the clamping member, whereby said rod will be actuated through the movement of the lay rod, and a yieldable clamping head at the upper end of the first rod, as and for the purpose set forth.

5. A tensioning device of the class described, including a rod having a channeled head portion, a movable block arranged within said head portion and a yieldable means disposed between the block and the head portion, as and for the purpose set forth.

6. The combination with a loom, of a tensioning device yieldably mounted upon the loom frame and actuated simultaneously with the movement of the lay for bracing against the lay on the forward beat of the same for retaining the filling thread in its respective position.

In testimony whereof we affix our signatures.

GROVER CLEVELAND HARALSON.
WILLIAM ERNEST TURNER.
